UNITED STATES PATENT OFFICE.

JAMES H. WATT, OF BARNESVILLE, OHIO.

CHIMNEY-CAP.

SPECIFICATION forming part of Letters Patent No. 276,102, dated April 17, 1883.

Application filed February 10, 1883. (No model.)

To all whom it may concern:

Be it known that I, J. H. WATT, of Barnesville, in the State of Ohio, have invented certain new and useful Improvements in Chimney-Caps; and I do hereby declare that the following is a full, clear, and exact description thereof, reference being had to the accompanying drawings, and to the letters of reference marked thereon, which form part of this specification, 10 in which—

Figure 1 is a perspective view of my improved chimney-cap complete. Fig. 2 is a perspective view of one of the corner-pieces. Fig. 3 is a top view of one of the mitered sections 15 of which the cap is composed.

This invention relates to chimney-caps which are made of metal; and the nature of it consists in a cast-metal chimney-cap which is composed of ribbed mitered sections united by 20 corner-pieces, as will be fully understood from the following description when taken in connection with the annexed drawings.

A A designate two mitered sections, which constitute the sides of an oblong rectangular chimney-cap, and B B are two mitered sections, which constitute the ends of the cap. These mitered sections are made of cast metal, and they are rigidly secured together at their corners by means of annular braces or corner-sections E, which are screwed or otherwise 25 secured to the bottoms of the sections flush with the edges thereof. Each mitered section is formed with a flat bottom and with two parallel ribs, a b, on its upper side, the object of

which is to give strength to the sections and 35 prevent them from cracking in the event of uneven setting of the chimney-top. The corner-pieces E are made of cast metal and constructed with three sides, as shown in Fig. 2, thus adapting them to serve as supports as 40 well as braces for the mitered sections or frame. I thus make a sectional frame which is adapted to cap the top of a chimney and to firmly bind together the top layers of bricks and prevent them from starting from their cement or fall- 45 ing off.

It is obvious from the above description that the corner E not only tie together the mitered sections forming the cap-frame, but that these corner-pieces fit snugly over the corners of the 50 top layers of bricks and serve as binders therefor.

Having described my invention, what I claim as new, and desire to secure by Letters Patent, 55 is—

A chimney-cap consisting of cast-metal ribbed and mitered sections united at their corners by cast-metal annular braces secured to the bottoms of the mitered sections, all constructed and adapted to operate substantially 60 in the manner and for the purposes described.

In testimony that I claim the foregoing as my own I affix my signature in presence of two witnesses.

J. H. WATT.
